CARD HOLDER

Application filed November 11, 1929. Serial No. 406,247.

This invention relates to improvements in visible index equipment and particularly to a card and signal mounting.

The invention is designed to provide a card holder which will engage and retain a card against movement therein and which is adapted for detachable cooperation with a suitable supporting element in such a manner that the card will be readily removable from the supporting element and at the same time will be effectively secured thereto in attached relation to prevent accidental disengagement.

One of the objects of the present invention is to provide a visible index in which cards or sheets of relatively cheap, light-weight material may have card holders readily applied thereto so that the sheets may be detachably connected to suitable supporting elements mounted in spaced relation so that the lower edges of the cards when lying upon the other will be relatively offset.

A further object of the invention is to provide a special signal member which is also movable on the support by a holder of the same type as used for the card. This permits independent mounting of the card and the associated signal on the same support, wherein either is independently demountable.

Another object of the invention is to provide a holder which will suitably space the inner edges of the cards from the supporting elements so that the cards may be freely rotated about the supporting elements on a plurality of card holders which are adapted to be simultaneously engaged or disengaged from the supporting elements.

The invention further comprehends the provision of visible index equipment utilizing these novel card holders with suitable supporting elements which are adapted to permit lateral shifting of the cards to offset certain cards with respect to others in an index panel, and with which a signal may be interchangeably associated. In this connection the invention includes a new combination in providing the mounting of the signal on the supporting element in detachable relation, independently of the detachable mounting for the index card.

A further feature of the invention resides in the providing the card mounting and holding structure with extra sheets one of which is adapted to be mounted with each card as a unit and to be retained in position by the special cooperation between the card, the sheet and the card holder.

The invention also comprehends numerous other objects residing in the combination of parts, and the specific construction and association of these parts which are more particularly pointed out in the following detailed description directed to the preferred forms of the invention, it being also understood, that various changes in the relation, construction and association of the parts may be made without departing from the spirit and scope of the invention as herein set forth.

In the accompanying drawings forming part of this application,

Fig. 1 is a perspective view of a card holder constructed in accordance with the present invention.

Fig. 2 is a fragmentary elevational view of a group of cards mounted on the supporting elements carried by a panel and showing the relation of the parts when assembled and also illustrating the manner in which one or more cards may be offset with respect to the others and a signal in cooperative relation with the cards.

Fig. 3 is a fragmentary elevational view showing the end portions of the holders in engagement with the panel.

Fig. 4 is a perspective view illustrating the clip by means of which a card is detachably secured to a holder.

Fig. 5 is a sectional view through a clip and holder in operative position.

Fig. 6 is an elevational view of a card in operative position on a holder and illustrating the position of the supplemental double-sheet structure when mounted in position thereon.

Fig. 7 is an enlarged fragmentary sectional view taken on line 7—7 of Fig. 6 and illustrating a plurality of the holders mounted in a tray and showing the manner in which the lugs maintain the holders in spaced relation with respect to each other.

Referring to the drawings, a panel or the like is indicated at 1 which may be of any desired form as used in connection with visible index equipment well known in the art, and is provided with guide channels 2 on the 5 opposite edges thereof. Card-supporting holders 3 are applied transversely of the panel 1 and have the end portions extending into the channels 2 by which they are secured in the panel, as shown in Fig. 1 in parallel relation. The card holders 3 are 10 preferably constructed as shown in Fig. 1 and comprise a flexible wire 4 the surface of which is preferably tinned.

Lugs 5 are molded onto the opposite ends 15 of the wire 3 for engagement with the channels 2 of the panel and are preferably formed with beveled outer ends 6 to facilitate their insertion between adjacent holders. A plurality of intermediate lugs 7 are also molded 20 around the wire 4 at spaced intervals from each other and are provided with oppositely extending foot portions 8 adapted to engage the corresponding foot portions of the lugs 7 on the next adjacent holders. The lugs 5 and 7 are preferably constructed of type 25 metal and are molded around the wire by suitable dies and unite with the tin surface of the wire thus preventing them from subsequently turning or becoming displaced thereon.

A card-engaging clip for association with the holders 3 is indicated at 9 in Fig. 4 and preferably comprises a thin strip of material 30 folded at its central portion as indicated at 10, one end portion of which is wider, as indicated at 11, than the opposite end portion 12. The portion 11 is substantially flat throughout its length and is adjacent the end portion 12 to provide a card-holding portion which is provided at the free end with a laterally extending flange 13 bifurcated, as indicated at 14, and having the terminals of 40 the bifurcated portion formed into a substantially U-shaped or semi-circular portion 15 extending from the flange 13 and adapted to embrace the wire 4 of the holder 3 between the lugs 7. The portion 12 of the clip 45 is tapered towards its free end, as illustrated in Fig. 4, which extends beyond the ends of the bifurcated portion 14 and beyond the wire embracing portions 15. The terminal portion of the portion 12 is slightly offset, as indicated at 16 to provide a wire-engaging 50 lip adapted to aid in the ready application of the clip to the wire of the holder.

The portion 12 is normally held by its own resiliency in substantial contact with the portion 11 so as to clamp the upper edge 60 portion of the card in the receiving portion of the holder and also to hold the wire-embracing portion 15 so as to clamp the clip in pivotal engagement with the wire 4. The clip is applied to a card 17 as illustrated in 65 Figs. 5 and 6 by insertion of the tongue 12

through a slot 18 formed in spaced parallel relation to the inner edge of the card so that the edge portion of the card is seated against the portion 11 of the clip. A pair of these clips is usually applied to a card, as illustrated in Fig. 6, adjacent to the opposite end portions.

The clips 9 are applied with the card to the wire 4 as shown in Fig. 6 with the wire-embracing portions 15 on the under side of the supporting elements while the tongues 16 are on the upper side thereof. To apply these clips to the wire they are grasped between the fingers placed at opposite ends of the card 17 and the offset portions 16 are moved into engagement with the supporting elements. Then, by depressing or pressing downwardly on the clips simultaneously the tongues 12 will be flexed to permit movement of the wire-embracing portions 15 and the portion 11 away from the portion 12 as a result of which the wire-embracing portions may be passed around and below the wire and the clips moved into the engaged position. When it is desired to remove the card and the clips from the supporting element this may be done by rotating the card to an inclined position about the wire and then through grasping the card and the clips adjacent to the portion 16 and pressing downwardly the tongues 12 will be flexed again to permit the movement of the portions 15 away from the wire as a result of which the holders may be readily and simultaneously detached.

When these clips are in the attached position the tongues 12 cooperate with the supporting engaging portions 15 in such a manner that by exerting a pull lengthwise or in the plane of the card 17, the card holders 105 will not become detached from the supporting elements. Accidental disengagements of the cards during normal use for indexing is thereby prevented.

With particular reference to Fig. 6, a sheet 19 is folded upon itself to form flaps or leaves 20 and 21 and is applied over the wire 4 in close proximity to the inner edge of the card. The leaf 20 is engaged against the front face of the card and may be flexed upwardly along its line of fold. The fold portion of the sheet 19 adjacent to the hinge is provided with elongated openings 22 through which the lugs 7 project. In assembly the lugs 7 on adjacent card holders cooperate with the card and the sheet to effectively retain the fold portion thereof in close proximity with the inner edge of the card. Thus the folded sheet is maintained against longitudinal displacement relative the panel 1 by adjacent holders and cards as shown in Fig. 7, and against lateral displacement by the engagement of the walls of its openings 22 with the sides of the lugs 7.

With the use of bar construction shown in

Fig. 1 in an assembled index structure as shown in Fig. 2 the card holders 9 may be applied so that the cards may be secured to the bars in either of two positions, providing for lateral offsetting of one or more cards with respect to the others to obtain advantages in filing systems used for accounting records. This offsetting may be obtained by removing the clips from the wires and remounting them thereon in the offset position. The arrangement of the cards as shown in Fig. 2 illustrates the positions in which the cards may be applied to the supporting wires 4 in obtaining this offsetting feature.

15 A further advantage of this offsetting feature is illustrated in Fig. 2 which shows how a signal may be advantageously mounted in a similar manner. The signal indicated at 23, is provided with a slot 24 at the inner end 20 for receiving one of the clips 9. The signal may be detachably applied to the supporting element structure, preferably between the two lugs, nearest the center for signalling cooperation with the card secured on the 25 same element. With this arrangement the signal, due to the resilient mounting of its clip, is slidably adjustable for a considerable range of lateral movement on the face of its accompanying card. This also provides an 30 independent mounting for the signal and the card so that they may both be readily applied and removed from the supporting wires.

The invention above described may be modified in construction and arrangement 35 without departing from the invention as defined in the appended claims.

What is claimed is:

1. A card holder for index or filing systems, comprising a wire, a lug secured to each 40 end of said wire for engagement with a panel, and intermediate lugs secured to said wire at spaced distances apart, all of said lugs being substantially of triangular cross-section to provide enlarged base portions for engagement with the back of the panel and with the corresponding lugs on the adjacent wire.

2. In combination, a supporting element having a plurality of spaced lugs thereon, an index card, and card holders on said card detachably engageable with said supporting element between said lugs.

3. In combination, supporting elements comprising wires having a plurality of lugs therein in spaced relation with respect to each 55 other, means for mounting said elements with the lugs of adjacent elements in abutting relation, a plurality of index cards, and card holders having resilient means removably engageable with said elements between 60 said lugs.

4. In combination, a supporting element comprising a wire having a plurality of lugs thereon in spaced relation with respect to each other, an index card, a card holder detachably mounting said index card on said

element between said lugs, a signal, and means independently mounting said signal on said supporting element between said lugs in signalling cooperation with said card.

5. In combination, a supporting element 70 comprising a wire having a plurality of spaced lugs thereon, a signal for index cards, and a holder engaged with said signal and detachably and resiliently connected to said wire for selective sliding movement between 75 two of said lugs.

6. In combination, a supporting element comprising a wire having a plurality of lugs thereon in spaced relation with respect to each other, an index card, a card holder associated with said card and detachably engaging said supporting element between said lugs in either of a plurality of positions, and a signal having holding means engageable with said supporting element between lugs in 80 either of said plurality of positions interchangeably with said card holder.

7. In combination, a supporting element comprising a wire having a plurality of lugs thereon in spaced relation with respect to 90 each other, an index card, a sheet folded upon itself to provide a pair of leaves and straddling said wire along its line of fold, said sheet having a plurality of perforations provided therein on said line of fold through 95 which said lugs are adapted to project to maintain said sheet against lateral displacement, a card holder for detachably securing said index card to said supporting element between said lugs.

8. In combination, a supporting element comprising a wire having a plurality of lugs thereon in spaced relation with respect to each other, an index card, card holders for detachably securing said index card to said supporting element between said lugs, a sheet folded upon itself and straddling said holder and said index card, said sheet having a plurality of perforations provided therein through which said lugs are adapted to project to prevent the lateral displacement of said sheet, said lugs being adapted to engage the back of a panel and prevent the displacement of said sheet from operative relation with respect to said card.

9. In combination, a supporting element comprising a wire having a plurality of lugs thereon, a sheet folded upon itself to provide a pair of leaves and straddling said supporting element along its line of fold, an index 120 card between the leaves of the folded sheet, and a card holder between the lugs on the supporting element detachably securing said card to the supporting element.
